UNITED STATES PATENT OFFICE.

MARY ELIZABETH NASSAU, OF PHILADELPHIA, PENNSYLVANIA, ASSIGNOR TO THE FIRM OF J. E. CALDWELL & COMPANY, OF PHILADELPHIA, PENNSYLVANIA.

DESIGN FOR A BADGE, PIN, OR SOCIETY-EMBLEM.

46,135.

Specification for Design.

Patented July 21, 1914.

Application filed May 26, 1914. Serial No. 841,166. Term of patent 14 years.

To all whom it may concern:

Be it known that I, MARY ELIZABETH NASSAU, a citizen of the United States, residing in the city and county of Philadelphia, State of Pennsylvania, have invented a new, original, and ornamental Design for a Badge, Pin, or Society-Emblem, of which the following is a specification, reference being had to the accompanying drawing, forming part thereof.

The figure is a face view of a badge, pin or society emblem, showing my new design.

I claim:

The ornamental design for a badge, pin or society emblem substantially as shown.

MARY ELIZABETH NASSAU.

Witnesses:

ALFRED F. PEYEGNAN,
JAMES GORDON AGNEW.
